UNITED STATES PATENT OFFICE.

JOSEPH EIFEL, OF CHICAGO, ILLINOIS.

EXPANSIBLE LOOSE-SHEET HOLDER.

Application filed September 1, 1921. Serial No. 497,609.

My present invention relates to filing appliances, and more particularly to expandible loose sheet holders of the type adapted to hold papers in a substantially vertical position between a series of filing leaves the distance between which may be varied as desired.

The principal objects of my present invention are the provision of a loose sheet holder having a series of leaves between which papers may be inserted, the provision of means whereby the file may be extended or contracted at will; the provision of improved means for preventing papers slipping down between the file leaves; the provision of means for facilitating the insertion of papers between the file leaves; and the provision of improved means for supporting such a file.

In attaining these and other objects and advantages to be hereinafter set forth, I have provided a construction, one embodiment of which is illustrated in the accompanying drawings, wherein:

Figure 1 is a plan view of the filing appliance;
 25 Figure 2 is a side elevation of the same;
 Figure 3 is a vertical section on the line 3—3 of Figure 1;
 Figure 4 is a vertical section through one of the file supporting members;
 30 Figure 5 is a partial side view showing a modified form of construction;
 Figure 6 is a partial side view showing a further modified form of construction; and
 Figure 7 is a detail view showing the sliding connections between one of the file leaves and the expandible device.

The filing appliance comprises a series of upwardly projecting leaves 1, of sheet metal or other suitable material supported by a lazy-tong device arranged underneath the file leaves. The use of lazy-tongs is advantageous as it gives a substantially rigid and inflexible support for the file leaves while allowing the distance between the file leaves to be increased or decreased simultaneously and also proportionately. The lazy-tong device consists of a plurality of links 2 each pivotally connected at four points to four other links of the lazy-tong device, as shown in Figure 1. 50 Two sets of these pivots 4 and 5 respectively are provided with means for supporting the file leaves. For this purpose the pivots 4 and 5 are made tubular in form for the reception of pins 7 having sliding frictional engagement therewith shown more particularly

in Figure 4. The upper part of these pins 7 are slotted for the reception of the lower edges, 15, of the file leaves, 1, as shown more particularly in Figures 3 and 4. Since the pivots, 4, approach the pivots, 5, as the appliance is extended, it is necessary that one set of pins, 7, have sliding engagement with the file leaves. In the form of construction shown the links passing through the pivots, 4, have sliding engagement with the file leaves 65 by means of slots, 36, in the file leaves and rivets, 37, passing therethrough. The pins passing through the pivots, 5, are rigidly connected to the file leaves, as shown in Figure 3. As the pins, 7, are detachable from the pivots, 70 any one or more of the file leaves may be detached from the lazy-tong device if desired.

Certain of the pivots 4 and 5 are also provided with rubber sleeves, 6, which act as supporting feet for the appliance. 75

The links of the lazy-tong are provided with extensions on one side downwardly turned at their ends to receive tabs, 10, the tips of which are curled upwardly and rearwardly as at 17 to form gripping means for 80 cardboard or other strips on which may be marked the contents of that particular part of the file.

In order to prevent papers slipping down between the file leaves and through the spaces 85 between the links of the lazy-tong device, I have provided members, 11, one longitudinal edge of which is provided with an upturned portion, 12, adapted to pass under and engage the lower edge of one file leaf, while the opposite longitudinal edge, 13, points toward the face of the opposite file leaf, resting thereupon when the appliance is in partly open position. In this connection it will be observed that the file leaves are bent slightly 90 about a line, 14, and that this line 14 is above the point of contact of the edge 13 with the file leaf, the planes of the two series of leaves thus intersecting. The object of this is to prevent the papers getting between the edge 95 13 and the file leaf with which it is in contact. The relation just described will be clear from inspection of Figure 3.

This change in the plane of the leaf 1 is also of advantage in that it causes the papers in 100 the file to lie flat against the upper portion of the leaves and the lowermost edges of the papers to rest against the adjacent leaf, with the paper in a substantially straight line. 105 Without the provision of this angle in the 110

leaves, the papers would tend to sag near the middle, and their lower edges to rest against various points along the base, thereby rendering the insertion of additional papers into the file more difficult.

The members, 11, are provided with apertures, 35, through which the extensions, 7, pass so that these parts, 11, are pivotally mounted on the projections 7. It has been found that the members, 11, move more readily if pins, 20, are arranged to pass through the pins, 7, underneath the upturned portions, 12, of these members.

In Figures 5 and 6 I have illustrated diagrammatically two modified forms of connecting members for preventing papers slipping down between the file leaves and through the lazy-tong device. In Figure 5 is shown a gusset 21 of leather or other suitable material connected along both edges at 22 to the adjacent file leaves. In Figure 6 a resilient member, 23, is used, connected along one edge only to one of the file leaves at the points 24. The opposite edge, 25, is held in contact with the opposite file leaf by the resiliency of the member, 23, which allows the file to be opened or closed without separating the edge 25 from its adjacent file leaf.

In order to facilitate the insertion of the papers between the file leaves, the lower corners, 16, of the file leaves are bent in the manner shown in Figure 2.

Having thus described my invention and illustrated its use, what I claim as new and desire to secure by Letters Patent is:

1. A filing appliance comprising in combination a series of file leaves, members movable relatively to said leaves, each having an upwardly turned end adapted to pass under the edge of one file leaf and an opposite end adapted to rest against the adjacent file leaf and thereby hold the contents of the file in place.

2. A filing appliance comprising in combination a series of file leaves, members each having an upwardly turned end adapted to pass under the edge of one file leaf and an opposite end adapted to rest against the adjacent file leaf and thereby hold the contents of the file in place, said file leaves being bent obliquely along lines above the points of contact of said last mentioned ends and the file leaves, whereby the contents of the file are prevented from coming between the file leaves and said members.

3. In an expandable filing appliance comprising in combination, a series of substantially parallel file leaves, members pivotally mounted adjacent the lower edge of each file leaf adapted to rest against the lower part of the adjacent file leaf and thereby support the lower edge of the contents of the file.

4. A filing appliance comprising in combination a series of file leaves, members pivotally mounted adjacent the lower edge of

each file leaf adapted to rest against the adjacent file leaf and thereby hold the contents of the file in place, said file leaves being bent obliquely along lines above the points of contact of said members and the file leaves, whereby the contents of the file are prevented from coming between the file leaves and said members.

5. A filing device, comprising, in combination, a series of file leaves, a horizontally expandable device for supporting said leaves without change in the vertical relation of said leaves, and pivotally mounted members interposed between said several leaves adapted to engage one edge of one file leaf and to point toward the lower part of an adjacent file leaf and thereby hold the contents of the file in place.

6. A filing appliance, comprising, in combination, a series of file leaves, a lazy-tong device arranged beneath said leaves, having substantially vertical pivots and upwardly projecting portions from certain of said pivots adapted to engage the lower portions of said file leaves, and members pivotally mounted on said projecting portions interposed between said several leaves adapted to engage one edge of one file leaf and to point toward an adjacent file leaf and thereby hold the contents of the file in place.

7. A filing appliance comprising, in combination, an expandable device, and a series of substantially vertical leaves carried thereby, said expandable device being adapted for iterated movement and to move said leaves toward and away from each other without relative lateral movement or angular movement relative to the longitudinal axis of said expandable device, said leaves and expandable device being releasably connected together frictionally, whereby the number of divisions in the appliance may be varied.

8. A filing appliance, comprising, in combination, a series of substantially vertical and parallel file leaves, an expandable device beneath said leaves, and connections between said file leaves and said device, said file leaves being bent obliquely along lines above the points of engagement between said file leaves and said connections, so as to present leaf portions lying in two different planes.

9. A vertical filing appliance, comprising, in combination, a substantially horizontal variably dimensioned base and a series of substantially parallel vertical file leaves variably displaceable and arranged at an angle to said base, the several members of the series having the plane of the upper portion bent at a slight angle to that of the lower portion.

10. A vertical filing appliance, comprising, in combination, a substantially horizontal base, a series of substantially parallel file leaves arranged at an angle to said base, and independent members pivotally mounted adjacent the lower edge of each file leaf adapted

to rest against the lower part of the adjacent file leaf and thereby hold the contents of the file in place.

11. In combination, a horizontally arranged variably dimensioned frame composed of crossed pivoted links, a plurality of substantially vertical partitions on said frame and variably positioned thereby, and a plurality of hinged sheet supporting elements arranged between said partitions near the lower ends thereof and angularly variably supported by said frame.

12. In combination, a horizontally arranged variably dimensioned frame composed of crossed pivoted links, a plurality of substantially vertical partitions on said frame and variably positioned thereby, and a plurality of angularly variable sheet sup-

porting elements variably supported by one of and arranged between adjacent to said partitions.

13. In combination, a horizontally arranged variably dimensioned frame composed of crossed pivoted links, a plurality of substantially vertical partitions on said frame and variably positioned thereby, and a plurality of angularly variably sheet supporting elements variably supported by one of and arranged between adjacent to said partitions, said elements being characterized by resiliency accommodating for variations in the dimensions of the device.

In testimony whereof, I have hereunto signed my name.

JOSEPH EIFEL
